(57) **CLAIM**

The ornamental design for a textile panel with a perforation pattern, as shown and described.

DESCRIPTION

The sole FIGURE is a top plan view of a textile panel with a perforation pattern according to my new design.

The bottom plan view of the textile panel with a perforation pattern shown in the sole FIGURE is the same as its corresponding top plan view. Accordingly, the bottom plan view is not illustrated. The dash-dot lines, defining the bounds of the claimed design, form no part thereof.
